Primary Examiner—James R. Largen*Assistant Examiner*—Doris Clark*Attorney, Agent, or Firm*—Nils H. Ljungman & Associates**[57] CLAIM**

The ornamental design for a beam, as shown and described.

DESCRIPTION

FIG. 1 is a perspective view of a beam showing my new design;

FIG. 2 is a side elevational view, the opposite side being a mirror image thereof; and,

FIG. 3 is an end elevational view, the opposite end being a mirror image thereof.
